CLAIM

The ornamental medical injector, as shown and described.

DESCRIPTION

FIG. 1 is a front right perspective view of the medical injector showing our new design in an active state; FIG. 2 is a top plan view thereof; FIG. 3 is a bottom plan view thereof; FIG. 4 is a right side elevation view thereof; FIG. 5 is a left side elevation view thereof; FIG. 6 is a rear end elevation view thereof; FIG. 7 is a front end elevation view thereof; FIG. 8 is a front right perspective view of the medical injector in a non-active state; FIG. 9 is a top plan view thereof; FIG. 10 is a bottom plan view thereof; FIG. 11 is a right side elevation view thereof; FIG. 12 is a left side elevation view thereof; FIG. 13 is a rear end elevation view thereof; and, FIG. 14 is a front end elevation view thereof. The broken line showing is for the purpose of illustrating portions of the article and forms no part of the claimed design.

1 Claim, 6 Drawing Sheets

Related U.S. Application Data

which is a continuation of application No. 14/449,671, filed on Aug. 1, 2014, now Pat. No. 9,744,307, which is a continuation of application No. 13/896,639, filed on May 17, 2013, now Pat. No. 8,827,962, which is a continuation of application No. 13/203,040, filed on Jan. 31, 2012, now Pat. No. 8,491,536.
